BATON TWIRLER

John A. Hooker, Kearny, N.J.

Application December 17, 1957, Serial No. 703,359

2 Claims. (Cl. 84—477)

This invention relates to baton twirlers, which conventionally require considerable dexterity and training for use. The invention eliminates the necessity of training and dexterity for the purpose of twirling a baton.

Pursuant to the invention, an elongated body member is formed for convenient resting in the palm of the hand and a cradle member is secured thereto for reception of the baton, so that the user need only flip the cradle member into rotation on the body member to rotate the baton with the cradle member, in simulation of the expert twirling action.

Examples of practical devices embodying the invention are described below and in the accompanying drawings; the invention is not limited thereto, but covers all other forms coming within the scope or purview of the disclosure herein.

In the drawings:

Fig. 1 is a perspective view of a device embodying the invention,

Fig. 2 is a similar view, showing the baton positioned therein and showing the outer perimeter of the baton twirled pursuant to the invention,

Fig. 3 is a vertical sectional view, taken on line 3—3 of Fig. 1, and

Fig. 4 is a fragmentary, medial, longitudinal sectional view, taken on line 4—4 of Fig. 1.

As shown in the drawings, the device of the invention comprises an elongated body member 10 which may be formed with a flat end 11 (Fig. 4) said body member being longitudinally tapered as shown at 12 (Fig. 1) to facilitate resting it in the palm of the user's hand. An elongated cradle member 13 is provided, having a continuous longitudinal recess 14, said recess being of transverse arcuate outline (Fig. 3) for the reception of the baton B therein. The cradle member 13 may be further cut away medially, longitudinally as at 15 (Fig. 1) to define end portions 16 which open upwardly and are provided with inwardly extended flanges 17 above the recessed portion 14, the parts being so proportioned that the baton may be inserted in the recess 14 or forced downwardly to first spread the flanges 17 for entry of the baton in the recess 14, whereupon the baton will be held firmly in place as shown in Fig. 2. The cradle member

2

may be made of plastic or other flexible material if desired, for that purpose, and has a flat end 18 on an extended boss 19 so that cradle member may be secured to the body member with the flat faces 11, 18 in abutment (Figs. 3 and 4). Complementary means are provided to rotatably secure the cradle member to the body member. Said means may comprise a stud 20 (Figs. 3 and 4) secured to or extended from the body member 10 and passing through an aperture 21 in the cradle member 13, said stud being upset, or flattened as at 22, said flattened portion 22 being formed in the cradle member 13 below the longitudinal recess 14 therein and opening into the medial groove 23 in said cradle member.

The baton B may be inserted in the twirler thus formed 15 and assembled and then the user may flip the cradle member into rotation on the body member, as shown in Fig. 2.

Having thus described my invention, what I claim as new and desire to secure by Letters Patent is:

1. A baton twirler comprising an elongated body member formed for convenient resting in the palm of a hand, a flat face on said body member, an elongated flexible cradle member having a continuous longitudinal recess of transverse arcuate outline, and opening upwardly, an extended boss at the lower end of said cradle member, a 20 flat face on said boss corresponding with the flat face of the body member, and complementary connecting means between said cradle member and said body member with their flat faces in abutment, so that the user may force fit a baton in the cradle member and then flip the cradle 25 member into rotation on the body member, thus rotating the baton with said cradle member.

2. A baton twirler comprising an elongated body member formed for convenient resting in the palm of a hand, an elongated cradle member having a continuous longitudinal recess of transverse arcuate outline, opening upwardly said cradle member being flexible and having flanges at the upper edge thereof extending inwardly of said longitudinally recessed portion, the parts being so proportioned that a baton may be inserted in the cradle 35 members and snapped past the said inwardly extending flanges of the cradle member and into the recessed portion thereof below said flanges and thereby frictionally held in the recessed portion of said cradle member, an extended boss at the lower end of said cradle member, and complementary connecting means between said cradle member and said body member so that the user may insert a baton in the cradle member and then flip the cradle member into rotation on the body member, thus rotating the baton with said cradle member.
